LIGHT STANDARD OR SIMILAR ARTICLE

Robert W. Selden, Seattle, Wash., assignor to
Weyerhaeuser Company, Tacoma, Wash.

Filed Oct. 20, 1969, Ser. No. 19,631

Term of patent 14 years

Int. Cl. D26—03

U.S. Cl. D48—31

FIG. 1 is a front elevational view of a light standard or similar article showing my new design;

FIG. 2 is a top plan view thereof.

FIG. 3 is an enlarged cross-sectional view taken on line 3—3 of FIG. 1.

FIG. 4 is an enlarged cross-sectional view of a second embodiment of my design, the cross section being taken on the embodiment on a plane identical to line 3—3 in FIG. 1, it being understood that the second embodiment differs from FIG. 1 only in cross section.

FIG. 5 is a front elevational view of a third embodiment of my design.

FIG. 6 is a top plan view thereof.

FIG. 7 is an enlarged cross-sectional view taken on line 7—7 of FIG. 6.

The rear of the light standard is identical to the front. The lamps are shown in broken lines in FIGS. 1, 2, 5

I claim:

The ornamental design for a light standard or similar article, as shown and described.
